HAIR FASTENER

Philip J. Graham, Leominster, Mass., assignor to
 Fosgood Corporation, Leominster, Mass., a corporation of Massachusetts

Application October 19, 1938, Serial No. 235,709

6 Claims. (Cl. 132—48)

This invention relates to an improvement in a fastener, and more particularly in a hair fastener or the like of the barrette type for adorning the hair and keeping it neatly in place.

10 The invention in this case is an improvement in the type of fastener in which the metal clasp that is clasped to the hair is hidden from view by a non-metallic artistically designed covering.

It has been found that the clasp often slips out 15 of the grasp of the ornamental covering. This invention therefore relates to a means for keeping the clasp in place and prevent its accidental slipping longitudinally of the covering. Also, this invention relates to a means for facilitating the speed of assembly of the clasp to the covering.

An object of this invention is to provide a positive locking means for the clasp to prevent its longitudinal displacement relative to the covering.

20 Another important object of this invention is to provide centering means for the clasp when assembling it to its cover thereby increasing the speed and accuracy of assembly.

Other objects and advantages of this invention 25 will become apparent as the description proceeds, reference being had to the accompanying drawing, in which:

Figure 1 is a front view of a hair fastener embodying my invention;

30 Fig. 2 is a rear view thereof with the lower leg of the clasp partly broken away;

Fig. 3 is a longitudinal sectional view thereof taken on the line 3—3 of Figure 1;

Fig. 4 is an enlarged cross-sectional view thereof taken on the line 4—4 of Fig. 3; and

35 Fig. 5 is a broken perspective view of the lower part of the clasp which is embedded in the non-metallic covering.

The metal clasp portion of the fastener is constructed of a springy metal and comprises a lower arm 10 and an upper arm 11 joined together by a bend 12. The arm 10 has a curved bent portion 13 at its end adapted to catch the end 14 of the arm 11 to hold the clasp around the hair when 45 worn.

The lower arm 10 in the vicinity of its longitudinal center has preferably two cut-out notches 15 and 16 for a purpose to be later described. Any number of notches and any shape therefor 50 may be used and they may be placed anywhere on the arm 10.

The covering for the metal clasp comprises a main body portion 17 of non-metallic material, preferably made of a hardened molded plastic or 55 thermo-plastic substance such as acetate, cellu-

lose composition, resins, Celluloid, or the like. The front face 18 may be formed or molded in any suitable ornamented shape or design, or it may be plain.

The back of this non-metallic covering is 5 formed with a longitudinal undercut groove 19 of a depth equal to the thickness of the arm 10 and of a width and side wall contour complementary to the contour of the sides of the arm 10 so that this arm may be fitted and embedded in 10 the groove without extending above the bottom surface of the covering. In other words, projections 20 and 21 are formed in the side walls of the groove 19 in number equal to and in shape complementary to the notches 15 and 16. In 15 assembled relation, the notches and projections interfit to form a centering means and a locking means for the clasp.

Two parallel longitudinally arranged flanges 22—22 molded or formed integrally with the bottom surface of the covering are arranged alongside the undercut groove 19. They project upwardly and at right angles toward each other and are adapted to receive and hold fast the lower arm 10 of the clasp. 25

For assembling the clasp to the ornamental cover, the arm 10 of the clasp is positioned in the groove 19 between the flanges 22—22 and positioned longitudinally so that the notches 15 and 16 fit over the complementary projections 20 and 21. The flanges 22 are then rolled or bent over the arm 10 to hold the clasp firmly in place. 30

After assembly the notches 15, 16 and projections 20, 21 act to retain the clasp in position and prevent its longitudinal displacement. 35

It may be readily seen that the projections 20 and 21 may be placed on the metal clasp and the complementary notches may be cut in the non-metallic covering. This equivalent construction is obvious to anyone skilled in the art and will 40 not need to be illustrated.

I do not wish to be limited to the exact details of construction herein disclosed but mean to include all equivalent structures as might fall within the scope of the appended claims. 45

What I claim is:

1. In a hair fastener of the character described, a clasp comprising two arms, one of said arms having notches therein, a cover for said clasp, projections extending from said cover arranged 50 to fit into said notches of said notched arm, said notches and projections cooperating to prevent accidental endwise displacement of said clasp relative to its cover.

2. In a hair fastener of the character described, 55

- 5 a clasp comprising two arms, one of said arms having notches therein, a cover for said clasp, projections extending from said cover arranged to fit into said notches of said notched arm, said notches and projections cooperating to center said clasp upon its assembly to the cover and thereafter acting to prevent accidental endwise displacement of said clasp relative to its cover.
- 10 3. In a hair fastener of the character described, a clasp member, a cover member for said clasp member, a groove in said cover member for receiving an element of said clasp member, notches cut in one of said members, complementary projections of the same shape as the notches extending from the other of said members adapted 15 to interfit with the notches in the notched member, whereby said clasp member is positioned relative to said cover member and is prevented from accidental displacement.
- 15 4. In a hair fastener of the character described, a clasp comprising two arms, one of said arms having notches therein, a cover for said clasp, a groove in said cover adapted to receive said notched arm, projections on the cover member extending into the groove adapted to fit into the notches of the notched arm, whereby to lock 20 said clasp against accidental displacement.
- 20 5. In a hair fastener of the character described,

a clasp comprising two arms, one of said arms having notches in its sides, a cover for said clasp, a groove in said cover adapted to receive said notched arm, means on said cover arranged longitudinally of said groove for clamping said arm 5 into said groove, projections extending from the side walls of said groove adapted to fit into the notches of the notched arm, said projections and complementary notches acting to center said clasp relative to said cover upon assembly and thereafter 10 acting to prevent accidental displacement of said clasp.

6. In a hair fastener of the character described, a clasp comprising two arms, one of said arms having notches therein, a cover for said clasp, an 15 undercut groove in said cover adapted to receive said notched arm, said groove having side walls, projections extending from the side walls of said groove adapted to fit into the notches of the notched arm, longitudinally arranged flanges extending along the sides of the groove above the 20 top surface thereof for clamping the notched arm into said groove, said projections and complementary notches acting to center said clasp relative to said cover upon assembly and thereafter 25 acting to prevent accidental displacement of said clasp.

PHILIP J. GRAHAM.
